UNITED STATES PATENT OFFICE.

THOMAS J. COOKSON, OF CINCINNATI, OHIO.

STEAM-TRAP.

No. 911,031.

Specification of Letters Patent.

Patented Feb. 2, 1909.

Application filed February 23, 1904. Serial No. 194,672.

To all whom it may concern:

Be it known that I, THOMAS J. COOKSON, a citizen of the United States of America, and resident of No. 2137 Grand street, Cincinnati, in the county of Hamilton and State of Ohio, (post-office address No. 1112 Traction Building, in the city of Cincinnati, county of Hamilton, and State of Ohio,) have invented an Improvement in a Steam-Trap; and I do hereby declare the following to be a full and exact description thereof, reference being had to the accompanying drawings, making part of this specification.

My invention relates to steam traps, and it has for its object the improvement in the construction of such devices whereby they are simplified and rendered more efficient in action.

The novelty of my invention consists in the combination and sub-combination of the parts, as will be hereinafter set forth and specifically pointed out in the claim.

Figure 1 is a longitudinal section of my steam trap. Fig. 2 is a section on line 2, 2, 25 of Fig. 1 with the cap and interior mechanism removed. Fig. 3 is an end view of the cap, looking from the inside of the trap. Fig. 4 is a side elevation of the interior mechanism of the trap. Fig. 5 is a vertical section 30 through the center of Fig. 4.

A represents the shell in which the mechanism of my trap is inclosed.

B is a cap which covers the opening A² of the shell A, to which it is attached by suitable cap screws. The inner side of the cap B has a shelf or projection B². In the center of the cap is a tapped hole to receive the regulating device B³. By screwing the regulating device B³ in until it hits the tail piece C¹⁵ the opening between chambers A³ and A⁴ is opened and the steam permitted to blow through the trap; this is for the purpose of removing any grit which might collect on the seat of the valve and thereby interfere with the proper working of the trap. After the objectionable material has been removed the regulating device is screwed back out of the way. The shell A is divided into two chambers, a large one A³ and a small one A⁴. Communication is had from the chamber A³ to the chamber A⁴ through the controlling mechanism C which is screwed into the tapped hole A⁵. The steam enters the trap through the tapped hole A⁶ and the condensed water which forms in the large chamber A³ passes from chamber A³ to chamber

A⁴ through the valve port between them, and leaves the trap through either the tapped hole A⁷ or A⁸, whichever may be most convenient. A small hole A⁹ is tapped in the top of the trap for an air valve if one is desired. The regulating device B³ is an ordinary threaded stem provided with a stuffing box to prevent the leakage of steam.

The controlling mechanism C is composed of the following parts: There is a plug C² which is screwed into the threaded hole A⁵; this plug C² has a valve seat C³ screwed into the top of it. The outside of the upper end of the plug C² is turned round and has 70 clamped to it by a small screw C⁴ a frame C⁵; the upper part of the frame C⁵ is provided with a round hole C⁶ through which the plunger C⁷ plays; the lower end of the plunger has screwed into it a plug C⁸ which conforms in shape with the valve seat C³, and when brought down so as to seat makes a water tight joint. The upper side of the plunger C⁷ is pivoted to the bell crank C⁹. The upper end of the frame C⁵ has attached 75 to it an ear C¹⁰, to which the lower end of the link C¹¹ is pivoted to the bell crank C⁹. A hole C¹² is tapped into the bell crank in which a rod C¹³ is screwed; the opposite end of the rod from the bell crank has on it an 80 ordinary float C¹⁴.

The operation of my device is as follows: Water flows in at the opening A⁶ until it raises the float C¹⁴, and as the float rises it causes the plug C⁸ to rise, permitting the 90 water to run out through the plug C⁸ into the chamber A⁴, and from this chamber it passes out from the trap either by the opening A⁷ or A⁸, whichever is most convenient.

Some of the features of my trap which 95 make it superior to ordinary traps are, the provision of a plate on which the water flows on entering the trap, so that any foreign matter that might be carried in by the water is not permitted to fall onto the working parts 100 of the outlet, but diverted to one side and caused to fall to the bottom of the trap below the working parts, thereby preventing any grit from getting between the plunger C⁷ and valve seat C³, which would cause the 105 valve to leak, either by preventing it from seating by remaining on the seat, or cutting it in passing through with the water.

Another feature which traps do not ordinarily possess is the convenient way in which 110 all the working parts can be removed from the shell A, which is as follows: The cap B

is removed, the screw C⁴ loosened and all the working parts can be removed by raising up the frame C, when it can be taken from the shell A. If the valve seat C³ or the plunger C⁸ should need grinding they can be easily removed by taking off the cap B and unscrewing them and putting others in their places, and no pipe connections are broken in removing any of the working parts.

10 What I claim is:—

The combination in a steam trap, of two independent chambers, a large chamber, and

a small chamber, the large and small chambers automatically connected by a valve and float within the large chamber, a stationary 15 plug between the large and small chamber to which is attached the frame which supports the valve mechanism, a clamp, and a screw C⁴, all substantially as described.

THOMAS J. COOKSON.
